E. G. BUSSE,
THIRD POINT SUPPORT FOR BRAKE BEAMS,
APPLICATION FILED FEB. 15, 1916.

1,182,454.

Patented May 9, 1916.

Inventor
Edwin G. Busse

By *J. C. Gammie, Atty.*

UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD-POINT SUPPORT FOR BRAKE-BEAMS.

1,182,454.

Specification of Letters Patent.

Patented May 9, 1916.

Application filed February 15, 1916. Serial No. 78,452.

To all whom it may concern:

Be it known that I, EDWIN G. BUSSE, a citizen of the United States, residing at Chicago, Illinois, have invented a certain 5 new and useful Improvement in Third-Point Supports for Brake-Beams, of which the following is a full, clear, and exact description, such as will enable others skilled in the art to which it appertains to make 10 and use the same, reference being had to the accompanying drawings, forming part of this specification.

Figure 1 is a side elevational view of my improved third point support for brake beams. Fig. 2 is a top plan view of the same.

This invention relates to a new and useful improvement in third point supports for brake beams of the character disclosed in 20 the patent granted to Charles Haines Williams, Jr., No. 997,888, on July 11, 1911.

The object of my present invention is to provide means to prevent the third point shoe from tilting upwardly over the beam 25 thereby occupying an abnormal position.

My present invention consists in the provision of a member mounted on the pivot pin of the third point supporting shoe, which member can be used with the types 30 of third point supports now in use.

In the drawings 1 indicates the strut of a trussed brake beam and 2 the tension member thereof.

3 is the outwardly extending nose shown 35 here as bifurcated between which bifurcated portions is located the pivoted end of the third point supporting shoe 4. 5 is the track with which such shoe co-operates.

6 is the pivot pin on which the shoe is 40 mounted.

7 is a casting pivotally mounted on the pivot pin and having cross members 8 and 9, which cross members are designed to contact with the parts of the brake beam in the event of any excess movement being imparted to the shoe and thereby retain said shoe in its normal working position. While I have shown cross pieces as being integral with the side pieces, all parts of this pivoted retaining member being integral, it is obvious that the cross pieces could be divided and two independent movable castings used. In assembling the parts, the casting is slipped over the end of the strut, the chair or shoe then inserted and finally the pivot 55 pin is introduced into position.

What I claim as new is:

1. A third point support for brake beams comprising a pivoted supporting member and a pivoted retaining member for preventing the supporting member from occupying an abnormal position. 60

2. A third point support for brake beams comprising a pivoted supporting member, and a pivoted retaining member having 65 means for contacting with the supporting member and a part of the brake beam, whereby the supporting member is prevented from occupying an abnormal position. 70

In testimony whereof I hereunto affix my signature in the presence of two witnesses, this tenth day of February, 1916.

EDWIN G. BUSSE.

Witnesses:

EDWARD T. WALKER,
M. F. HUNTOON.
